(57) CLAIM

The ornamental design for a shoe, as shown and described.

DESCRIPTION

FIG. 1 is a front perspective view of a shoe showing my new design; and,

FIG. 2 is a side view thereof.

The even-length broken lines within the shaded region represent stitching that forms part of the claimed design. The uneven-length broken lines immediately adjacent to the top edge of the shaded area define the bounds of the claimed design and form no part thereof. The circular uneven-length broken line near the end of the strap and the unshaded area within forms no part of the claimed design. The uneven-length broken lines depicting the remainder of the shoe form no part of the claimed design.
